UNITED STATES PATENT OFFICE.

JOHN Q. SHERMAN, OF DAYTON, OHIO.

MANIFOLDING REGISTER.

Application filed February 7, 1921. Serial No. 443,009.

To all whom it may concern:

Be it known that I, JOHN Q. SHERMAN, a citizen of the United States, and a resident of the city of Dayton, in the county of 5 Montgomery and State of Ohio, have invented certain new and useful Improvements in Manifolding Registers, of which the following is a full, clear, and exact description, reference being had to the drawings forming part of this specification.

My invention relates to devices for feeding a plurality of superimposed strips or webs of paper in true alignment, for purposes of forming like impressions on the 15 webs while in superimposed position. Machines of this character include autographic registers, flat bed typewriting manifolding machines, and manifolding typewriters of various kinds to all of which machines my 20 invention is applicable.

The object of my invention is to provide a form of pin feed for paper, whereby a pin will enter aligned apertures therein and move through a path while in engagement 25 therewith, which embodies not only a movement to draw the paper through a straight path, but also a lengthwise movement with relation to the paper so as to accomplish a thrusting motion in entering the said apertures.

The usual type of pin feed mechanism comprises a pin or series of pins mounted on a rotary member, and moving around, so as to bring the pins into the paper at 35 the upper end of the circular movement together with some means for preserving a path for the paper that is substantially tangential to the said rotary member. As can be readily observed, the chance for 40 defective operation in such a feed arises in cases where the rotary bodies are of such size or the pin spacing or path of the paper such as to bring a number of pins into contact with the paper at the same time, 45 with the resulting tendency of the entering and departing pins tearing out the edges of the apertures.

By means of my present invention, the 50 advantages of the pin feed in the various kinds of machines mentioned, are preserved, while by imparting a thrust and retraction to the pins, I may accomplish a quick full engagement, and a complete withdrawal without mutilation. Also, the necessity of 55 carefully guarding the path of the paper is somewhat obviated, because the dangers in

departure from a true tangential path are not evident.

The above objects and other advantages to be noted, I accomplish by that certain 60 construction and arrangement of parts to be hereinafter more specifically pointed out and claimed.

In the drawings—

Figure 1 is a side elevation, partly broken 65 away of a rotary feed pin device, constructed according to my invention.

Figure 2 is a front elevation, showing a detail of a feed shaft and feed pin device, 70 of the type illustrated in Figure 1.

Figure 3 is a detail side elevation showing a form of composite pressure roll and feed pin mechanism.

Figure 4 is a front elevation, showing in detail the parts illustrated in Figure 3.

Figure 5 is a perspective detail, showing 75 the feed pin device, as employed with a sliding bar feed for paper.

Figure 6 is a front elevation partly in section, showing the same parts illustrated in 80 Figure 5 with the addition of the feed shaft, and rack and pinion device for moving the sliding bar.

Figure 7 is a detail plan view, with a 85 partial elevation developed therefrom, illustrating the extensible roller guide and switch, which controls the idle return of the pins in the sliding bar type of feed. Figure 8 is a detail section of a spring return device for the parts shown in Figures 5—7. 90

It will be noted above, that I have shown several types of feeds, in each of which the longitudinally moving pin is shown, and in each of which the pin moves in a path to feed the paper. In each instance, also, a 95 fixed cam is employed for the purpose of imparting the longitudinal movement to the pin, although this is not intended as illustrating the only possible method which occurs to me of accomplishing this movement. Neither do I, because of the showing of various modifications, intend to carry the meaning that no other uses of modifications occur to me, for my invention.

Referring first to the forms shown in Figures 1 to 4 of the drawings, I wish to note 105 that there are two types of feed shown therein, both of which are applicable to manifolding machines having a flat writing table or bed, or having a rotary platen, 110 against which the writing is done.

In Figures 1 and 2, the feed shaft is

- shown at 1, having a handle 2, which carries a disk 3. This disk has a rib 4, along an inner edge of the periphery which is perforated with holes for the feed pins 5.
- 5 Mounted against the side of the disk are a set of plates 6, making up an annular flange which is also perforated for the pins, said pins lying between the rib and flange member, and having springs 7 coiled around them. The springs tend to keep the pins in a position with their ends retracted to within the bounds of the periphery of the disk.
- 10 Held on a bar 8 which is mounted transversely of the disk, is a cam 9, of the desired shape, which lies within the space outlined by the rib and flange member, and against which the ends of the pins will bear, thereby thrusting them out through the rib, into a position for paper engagement.
- 15 20 While no specific machine is shown in connection with Figures 1 and 2, it will be understood that one or more of these feed pin devices may be mounted on a feed shaft or platen, and that preferably a rib 10 will be formed along-side of the pins to serve the function of keeping away from a binding contact with the periphery of the disk or disks, such pressure member as is used for keeping the paper down on the pins.
- 25 30 In operating such a device when mounted in a manifolding machine or typewriter, the operator sets the paper, with its holes down over the pins, all webs aligned as desired, and then turns the feed shaft, which 35 will give a thrust and withdrawal to the pins, and also a motion through a feed arc. The shape of the cam, as has been said, is a matter of preference, dependent upon the nature of feed desired.
- 35 40 Turning to Figures 3 and 4, it will be noted that in this case I have shown a roll or platen 11, operated by a shaft 12, which roll or platen works against a pressure roll 13, held on small bell cranks 14. Also on 45 the shaft is a cam 15, which operates with the feed shaft to raise up the roll 13 at the time of feed pin engagement.
- The feed pin is carried by the rib 17 at the end or ends of the roll or platen, there 50 being in this case but one feed pin in each rib portion. The pin has an enlarged head 18 and a shank 19, and the hole 16 in the rib is too small at the base for passage of the head, thereby doing away with the 55 flange member of the first modification. The spring 20 encompassing the pin bears against the base of the hole in the rib and is secured at its other end to the pin itself.
- 60 65 An arm 21 carries the cam piece 22 against which the pin finds a bearing during its path with the platen, this period of contact corresponding with the position of the cam 15.
- 65 To impart spring pressure to the roll 13,

I mount in a small guide 23, suitably supported in fixed position relative to the machine, a sliding piece 24, which is under the influence of a spring 25 dropped into the guide and held there by a screw plug 26. A finger 27 is pivoted to the guide piece and may be used to throw up the sliding piece.

The sliding piece bears against the bell crank 14, and thus presses the roll down against the platen. Where the mounting devices for the roll 13 are rigid and non-bendable, it will not be necessary to duplicate this spring structure for both ends of the roll. To hold the roll in raised position, a finger 28 may be provided which engages 80 behind a notch in the bell crank when the roll is raised.

The device now described operates as follows: after the operator has mounted the paper in the machine and set it with its 85 alignment holes over the pin, or pins, should the pin feature be duplicated for both ends of the roll or platen, he turns the handle on the roll or platen shaft, which acts to move the pin and feed the paper between the 90 platen and the pressure roll 13. When the pin comes uppermost it will be thrust longitudinally into engagement with the next aperture in the paper, and at the same time the upper roll 13 will be raised by the cam. 95 The feed pin will then move around on the shaft as a center, drawing the paper along with it, and aligning the forms on the various superimposed webs, said webs being free to slide on each other, and thus adjust 100 themselves on the pin.

This feed pin operation will continue for a short space after which the pin will be sharply retracted from the paper, because of the lower end of the pin sliding off the cam. 105 The timing of the feed pin operation with reference to the balance of the feed may be as desired. The slot 13^a in the roller 13 gives pin clearance at all times.

In the modification shown in Figures 5, 6 110 and 7, I show a manifolder having a flat bed or writing table 40, beneath which are a pair of guides 41 extending lengthwise of the bed, and mounting slidably the bars 42. But one set of these bars are shown, but it 115 will be understood that they may be duplicated or not as desired. The bar has a rack 43 on its under side, and the feed shaft 44 has a pinion 45 which engages the rack.

Within this sliding bar or bars are formed 120 suitable holes 46 for a series of interspaced pins 47, these pins being fitted with springs 48, within the holes, and held against falling out by strips 49 closing the holes except for sufficient clearance for the shank of the pins. 125

Mounted on a grooved bracket 50 at one side of the machine is a sliding frame 51, which carries a cam 52, against which the pins bear which are carried in the bar.

Thus at a desired point in the machine, 130

the movement of the sliding bar will result in the pins being forced up above the level of the writing table, with which the bar is flush, thereby causing them to engage in

the pins and allowing the sliding bar to return to its original position without affecting the paper in any way.

5 suitably formed alignment apertures in the paper to be fed. The pins will also have a path of movement with the bar, so as to feed the paper, while maintaining a vertical position at all times.

If it is desired to avoid the necessity of withdrawing the sliding bar by a reverse 70 turning of the handle, it may be retracted by a spring secured to the bar, or shaft and constantly tending to retract it. The feed shaft may accordingly have a pawl carrier 70 thereon (Figure 8), on which will be 75 mounted a spring pawl 71, which pawl meshes with a ratchet 72, secured against the face of the driving pinion 45 of the feed. The pinion will in such a case be loose on the shaft instead of tight as illustrated in the first instance. The spring 73 will be held in a housing 74 mounted on the machine frame and also secured to the collar 75 of the gear 45. A pawl trip 76 located adjustably by a screw 77, engaging in a slot 78 thereof will trip 85 the pawl, permitting a spring return at the desired point, dependent upon the feed adjustment.

10 A pressure roll 53 is mounted over the writing table at the feeding point and normally rests on a plate 54 mounted against the outside of the sliding bar, so as to remain in a position out of clamping contact 15 with the paper while it is being fed. A reduced end 55 to the plate permits the roll to fall when the sliding bar is entirely retracted and during its forward motion, the plate rides on a roller 56, which said roller 20 is mounted on the sliding frame 51, above referred to. The plate 54 is mounted on the bar by screws 54^a, having sleeves that engage in slots 54^b, so that the roller 56 is enabled to accurately position the said plate.

It is believed that the operation of my various modifications will be evident from 90 above without further remark, and that I have sufficiently indicated above that the fact of showing several of the modifications which occur to me is not to be taken as excluding other merely mechanical changes, 95 which may occur to those skilled in the art in question.

Having thus described my invention, what I claim as new and desire to secure by Letters Patent, is:—

100

1. In a manifolding machine, the combination with a paper support, of a pin carrier, having slidable pins therein, said pins being adapted to engage holes in manifolding paper, and feed and align the webs thereof, 105 means for moving the carrier in a rectilinear path and abutment means to thrust the pins into paper engagement at a common point during the movement of the carrier.

2. In a manifolding machine, the combination with a paper support, of a pin carrier, having slidable pins therein, said pins being adapted to engage holes in manifolding paper, and feed and align the webs thereof, 110 means for moving the carrier in a rectilinear path and abutment means to thrust the pins into paper engagement at a common point during the movement of the carrier, said means being shiftable to permit a return movement of the carrier without affecting 115 the pins.

3. In a manifolding machine, the combination with a paper support, of a pin carrier, having slidable pins therein, said pins being adapted to engage holes in manifolding 125 paper, and feed and align the webs thereof, means for moving the carrier in a rectilinear path and abutment means to thrust the pins into paper engagement at a common point during the movement of the carrier, means 130

25 The frame 51 is shifted laterally to permit the bar to return without the pins being thrust above the level of the writing table or platen. To accomplish this, there is mounted on an arm 57, a roller 58, which 30 during the motion of the sliding bar, rides against a switching device on the under side of the said bar. The arm 57 is on the sliding frame 51 and a spring 59 engaging between the sliding frame and the wall of the machine, keeps the said roller against the switching device.

As a switching device I employ a pair of plates 60, 61, which have a cut-away portion at 62, to permit of an overlap for adjusting length of feed. The piece 61 is secured in permanent position on the under side of the bar and the piece 60 is adjustably mounted on screws 63, engaging in a slot 64 in the piece. Extra screw holes as 45 at 65 may also be provided and it may be observed that I thereby provide an extensible rib or bar against which the roller 58 will ride.

At the end of the piece 61 it is equipped 50 with a swinging arm 66, pivoted at 67 and provided with a spring 68, which normally keeps this arm 66 up against a diverting plate 69.

The structure operates as follows: the 55 movement of the main slide bar will bring the pins seriatim up through the holes in the paper at the feeding point, the cam device being held in position to act on the pins during this motion, by the roller 58 riding against the switching device. As the sliding bar reaches the forward end of its stroke, dependent upon the adjusted length 60 of the switching mechanism, the roller 58 is sprung around the end of the bar 60, thereby 65 permitting the cam to ride out of the way of

- to keep the paper on the support in position for engagement with the pins, without exerting pressure upon the paper and means for maintaining said means in a non-pressure exerting position. 5. In a manifolding machine, the combination with a paper support, of a pin carrier, having slideable pins therein, said pins being adapted to engage holes in manifolding paper, and feed and align the webs thereof, means for moving the carrier in a rectilinear path and abutment means to thrust the pins into paper engagement at a common point during the movement of the carrier, means to keep the paper on the support in position for engagement with the pins, without exerting pressure upon the paper and means for maintaining said means in a non-pressure exerting position, said means being relaxable automatically at points of rest between feeding operations to come into paper clamping positions. 6. In a manifolding machine, the combination with a paper support, of a slideable bar, pins movable in the bar, contact means to engage and move the pins into engagement with paper on the support, at a given point in the path of the bar, and automatic means for shifting said contact means out of contact position with the pins at the end of each feeding operation. 7. In a manifolding machine, a paper support, a member located over the support at a given position to keep the paper on the support without frictionally engaging the paper, clearance spaces for pins to rise through the support, and engage the paper beneath said member, and a carrier movable rectilinearly beneath the support, movable pins in the carrier and a contact means located beneath the support and the above noted member, to thrust the pins upward into the paper during the movement of the carrier, as and for the purpose described. 8. In a manifolding machine, the combination with a paper support, of a pin carrier, having slideable pins therein, said pins being adapted to engage holes in manifolding paper, and feed and align the webs thereof, means for moving the carrier in a rectilinear path and abutment means to thrust the pins into paper engagement at a common point during the movement of the carrier, means for moving the carrier, a spring return device for the carrier, and means for disconnecting the moving means and coupling the spring return. 9. In a manifolding machine the combination with a paper support, of a pin carrier, having slideable pins therein, said pins being adapted to engage holes in manifolding paper, and feed and align the webs thereof, means for moving the carrier in a rectilinear path and abutment means to thrust the pins into paper engagement at a common point during the movement of the carrier, means for moving the carrier, a spring return device for the carrier, and means for disconnecting the moving means and coupling the spring return, said means comprising a contact element, adjustably positioned with relation to the path of the carrier. 10. In a manifolding machine, the combination with a paper support, of a pin carrier, having slideable pins therein, said pins being adapted to engage holes in manifolding paper, and feed and align the webs thereof, means for moving the carrier in a rectilinear path and abutment means to thrust the pins into paper engagement at a common point during the movement of the carrier, said means being shiftable to permit a return movement of the carrier without affecting the pins, means for moving the carrier, a spring return device for the carrier, and means for disconnecting the moving means and coupling the spring return, coincidental with the shifting of the abutment means. 11. In a manifolding machine, the combination with a paper support, of a pin carrier equipped with sliding pins, and movable beneath the support in a path parallel with the support, a movable abutment positioned at a given point and adapted to thrust the sliding pins into a position of paper engagement at said point during the movement of the carrier, a switch mechanism on the carrier, and means for maintaining the abutment on the switch mechanism, whereby at a given point the abutment will be moved out of engagement with the pins. 12. In a manifolding machine, the combination with a paper support, of a pin carrier equipped with sliding pins, and movable beneath the support in a path parallel with the support, a movable abutment positioned at a given point and adapted to thrust the sliding pins into a position of paper engagement at said point during the movement of the carrier, a switch mechanism on the carrier, and means for maintaining the abutment on the switch mechanism, whereby at a given point the abutment will be moved out of engagement with the pins, said switch mechanism being adjustable for length.

JOHN Q. SHERMAN.
